UNITED STATES PATENT OFFICE.

CHARLES SZALAI, OF EASTON, PENNSYLVANIA.

STOVE-LID LIFTER.

Application filed April 14, 1922. Serial No. 552,694.

To all whom it may concern:

Be it known that I, CHARLES SZALAI, a citizen of Hungary, residing at Easton, in the county of Northampton and State of Pennsylvania, have invented certain new and useful Improvements in Stove-Lid Lifters, of which the following is a specification.

This invention relates to certain new and useful improvements in stove lid lifters, of 10 that type wherein means is provided for preventing accidental dropping of the stove lid when removing the same.

The primary object of the invention is to provide a stove lid lifter of the above kind 15 which is of extremely simple construction and which will prove durable and efficient in use.

Another object of the invention is to provide a stove lid lifter composed of a minimum 20 number of simple and durable parts which may be cheaply manufactured and assembled and conveniently operated for lifting lids of stoves without danger of dropping the latter.

With the above general objects in view the invention consists of the novel combination and arrangement of parts hereinafter more fully described in connection with accompanying drawing, and in which like 25 reference characters designate corresponding parts throughout the several views.

In the drawings forming a part of this application and in which like designating characters refer to corresponding parts 30 throughout the several views:

Figure 1 is a view partly in side elevation and partly in section of a stove lid lifter constructed in accordance with the present invention and with the retaining jaw shown 35 in operative position by dotted lines,

Figure 2 is a front elevational view of the device shown in Figure 1,

Figure 3 is a view similar to Figure 1 of the preferred form of the invention, and

Figure 4 is a sectional view taken substantially upon line IV—IV of Figure 3.

Referring more in detail to the several views, and particularly to Figures 1 and 2, the invention embodies a body portion 5 of 50 suitable metal with a handle 6 integral with one end thereof and extending laterally in one direction at an obtuse angle to the said body portion, the body portion 5 having a jaw member 7 integral with the other end 55 thereof formed and adapted to engage in the recess of a stove lid and extending at an ob-

tuse angle to the body portion 5 in the opposite direction.

The jaw 7 is preferably of curved form as shown and is provided with a transverse 60 slot 8 near its juncture with the body portion 5 and in which one end of a pivoted clamping jaw 9 is mounted as at 10, the jaw 9 being curved in the opposite direction to the curvature of the jaw 7 and arranged 65 so that the extreme free ends of the jaws 7 and 9 will normally contact as shown by full lines in Figure 1.

The body portion 5 is provided with a longitudinal bore 11 in which is slidably fitted 70 a push rod 12 having one end pivotally attached as at 13 to the adjacent end of the jaw 9 inwardly of the pivot pin and having its other end projecting above the adjacent portion of the handle 6 and terminating in a 75 push bottom or head 14, the arrangement being such that depression of the push button 14 will cause swinging movement of the jaw 9 away from the jaw 7 as indicated by dotted lines in Figure 1.

The bore 11 is enlarged as at 15 at the point of juncture between the body portion 5 and handle 6 so as to provide a socket in which one end of a helical spring 16 is seated, the spring 16 being arranged to surround 85 the rod 12 and has its other end bearing against the under side of the push button or head 14 so that the push rod 12 is normally projected upwardly for holding the jaw 9 lowered in engagement with the jaw 7 as 90 shown by full lines in Figure 1.

In using the device, the handle 6 is grasped by the user and the jaw 7 is inserted in the under cut recess usually provided in stove lids so that the free end of the jaw 7 engages 95 the under surface of the top wall of the recess, this being permitted by depression of the head 14 so that the jaw 9 is swung away from the jaw 7 as indicated by dotted lines in Figure 1. It will be understood that the push button 14 is kept depressed until the jaw 7 is engaged in the recess as mentioned, and then upon release of the push button 14, the spring 16 will pull upwardly upon the rod 12 so as to swing the jaw 9 toward the 105 jaw 7 for engaging the free end of said jaw 9 with the upper surface of the top wall of said recess so that the lid will be effectively clamped. Obviously the lid may then be lifted without danger of dropping the same, 110 the spring 16 being of relatively great strength for this purpose.

Referring to Figures 3 and 4, the invention embodies the body member 5' with the integral handle 6' at one end and the integral jaw 7' at the other end, the handle 6' and jaw 7' being extended in opposite directions as in Figure 1. The body portion 5' is provided with a longitudinal bore 11' in which is slidably mounted a push rod 12' having a push button or head 14' upon its upper end and pivotally attached as at 13' to the adjacent end of the pivoted jaw 9' which is mounted as at 10' in the recess 8' of the integral jaw 7'. Thus far described, the invention is the same as in Figure 1, but instead of utilizing a helical spring 16 as shown in Figure 1 between the head 14 and body member 5, the same is dispensed with in Figure 3 and a leaf spring 16' is employed between the body member 5' and jaw 9' as shown. In order to provide for attachment of the spring 16', the body portion 5' is provided with a pair of spaced ears 17 connected by a pin 18 and upon which one end of the spring 16' is secured, the other end of said spring being secured upon a similar pin 19 connecting a pair of spaced ears 20 provided upon the jaw 9' intermediate the free ends of the latter and a pivot pin thereof. The spring 16' is of upwardly and outwardly curved form and of sufficient strength to urge the jaw 9' toward the jaw 7' with considerable force so that the free ends of the jaws will effectively clamp against the opposite faces of the top wall of the under cut recess 8' of the stove lid. The operation in connection with this form is substantially the same as with the form in Figure 1 above described.

From the foregoing description, it is believed that the construction and operation as well as the advantages of the present invention will be readily understood and appreciated by those skilled in the art.

Minor changes may be made without departing from the spirit and scope of the invention as hereinafter claimed.

Having thus fully described the invention, what I claim as new is:-

1. A stove lid lifter comprising a body portion having a longitudinal bore with a push rod slidably disposed therein and terminating above the upper end of the body portion and below the lower end of said body portion, a handle integral with and extending rearwardly from one end of the body portion in one direction, a jaw member rigid with the opposite end of the body portion and extending laterally from the latter in the opposite direction, said jaw member having a transverse recess, a second jaw member pivotally mounted in the recess of the first named jaw member and arranged so that the free ends of said jaw members may clampingly engage opposite faces of the top wall of the under cut grooves of a stove lid, the lower end of the push rod being pivotally attached to the inner end of said pivoted jaw whereby depression of the push rod will cause swinging movement of the pivoted jaw away from the first named jaw, and yieldable means normally urging the pivoted jaw toward said first named jaw.

2. A stove lid lifter comprising a body portion having a longitudinal bore with a push rod slidably disposed therein and terminating above the upper end of the body portion and below the lower end of said body portion, a handle integral with and extending rearwardly from one end of the body portion in one direction, a jaw member rigid with the opposite end of the body portion and extending laterally from the latter in the opposite direction, said jaw member having a transverse recess, a second jaw member pivotally mounted in the recess of the first named jaw member and arranged so that the free ends of said jaw members may clampingly engage opposite faces of the top wall of the under cut grooves of a stove lid, the lower end of the push rod being pivotally attached to the inner end of said pivoted jaw whereby depression of the push rod will cause swinging movement of the pivoted jaw away from the first named jaw, and yieldable means normally urging the pivoted jaw toward said first named jaw.

3. A stove lid lifter comprising a body portion having a longitudinal bore with a push rod slidably disposed therein and terminating above the upper end of the body portion and below the lower end of said body portion, a handle integral with and extending rearwardly from one end of the body portion in one direction, a jaw member rigid with the opposite end of the body portion and extending laterally from the latter in the opposite direction, said jaw member having a transverse recess, a second jaw member pivotally mounted in the recess of the first named jaw member and arranged so that the free ends of said jaw members may clampingly engage opposite faces of the top wall of the under cut grooves of a stove lid, the lower end of the push rod being pivotally attached to the inner end of said pivoted jaw whereby depression of the push rod will cause swinging movement of the pivoted jaw away from the first named jaw, and yieldable means normally urging the pivoted jaw toward said first named jaw, said jaws being of oppositely curved formation with the pivoted jaw overlying the first named jaw.

4. A stove lid lifter comprising a body portion having a longitudinal bore with a push rod slidably disposed therein and terminating above the upper end of the body portion and below the lower end of said body portion, a handle integral with and extending rearwardly from one end of the body portion in one direction, a jaw member rigid with the opposite end of the body portion and extending laterally from the latter in the opposite direction, said jaw member having a transverse recess, a second jaw member pivotally mounted in the recess of the first named jaw member and arranged so that the free ends of the jaw members may clampingly engage opposite faces of the top wall of the under cut grooves of a stove lid, the lower end of the push rod being pivotally attached to the inner end of said pivoted jaw whereby depression of the push rod will cause swinging movement of the pivoted jaw away from the first named jaw, and yieldable means normally urging the pivoted jaw toward said first named jaw, said jaws being of oppositely curved formation with the pivoted jaws overlying the first named jaw, and said first named jaw and handle extending at an obtuse angle from the body portion.

5. A stove lid lifter comprising a body portion having a longitudinal bore with a push rod slidably disposed therein and ter-

minating above the upper end of the body portion and below the lower end of said body portion, a handle integral with and extending rearwardly from one end of the body portion in one direction, a jaw member rigid with the opposite end of the body portion and extending laterally from the latter in the opposite direction, said jaw member having a transverse recess, a second jaw member pivotally mounted in the recess of the first named jaw member and arranged so that the free ends of said jaw members may clampingly engage opposite faces of the top wall of the under cut grooves of a stove lid, the lower end of the push rod being pivotally attached to the inner end of said pivoted jaw whereby depression of the push

rod will cause swinging movement of the pivoted jaw away from the first named jaw, and yieldable means normally urging the pivoted jaw toward said first named jaw, the pivoted jaw and the body portion being each provided with a pair of spaced ears connected by a pin, and said yieldable means for urging the pivotal jaw toward the first named jaw comprising an arcuate leaf spring having the ends thereof secured on said ear connecting pins.

In testimony whereof I affix my signature.

CHARLES SZALAI.
